JOHANN STUMPF, OF BERLIN, GERMANY.

STEAM-ENGINE.

1,201,383.

Specification of Letters Patent. Patented Oct. 17, 1916.

Application filed May 14, 1914. Serial No. 838,482.

To all whom it may concern:

Be it known that I, JOHANN STUMPF, a subject of the Emperor of Germany, residing in Berlin, W., Germany, have invented 5 a new and useful Improvement in Steam-Engines, of which the following is a specification.

This invention relates to improvements in steam engines, and is especially directed to 10 the arrangement, position and control of the valves thereof.

The object is to provide improved means for facilitating the coasting of locomotives, whereby the coasting automatically begins as 15 soon as the driving steam is shut off.

The object is also to eliminate the necessity for providing a large clearance volume with large surfaces, which involve loss, for 20 the introduction of the large quantity of compression steam ordinarily required.

Referring to the drawings, which illustrate merely by way of example, a suitable embodiment of my invention—Figure 1 is a 25 partial longitudinal section of a locomotive cylinder of the una-flow* type. Fig. 2 is a vertical section through the locomotive cylinder with the main valve gear in modified form. Fig. 3 is a plan and part horizontal section of arrangements shown in Fig. 2. 30 Similar numerals refer to similar parts throughout the several views.

The attempt has already been made to devise an arrangement for coasting in mountain work on locomotives built on the una- 35 flow principle, in that both inlet valves have been opened and held open by the valve gear. The contents of the cylinder would then be pushed back and forth by the piston through the open inlet valves and the common steam 40 chest. With this arrangement a special design of gear and a special setting of the same for coasting was necessary.

According to the present invention the 45 outlet valves will be placed near the ends of the cylinder and in communication therewith. These outlets may coöperate with another exhaust valve gear; such, for example, as an exhaust port arrangement provided with the usual exhaust pipe. These outlet 50 valves are controlled in a well known manner by the excess of pressure in the cylinder on one side and a spring on the other, so that they open and close automatically according to the internal pressure, remaining 55 open whenever atmospheric or higher exhaust pressure, as the case may be, prevails

in the cylinder. The contents of the cylinder will then be forced to and fro through these outlet valves and their common passages by the piston. The common exhaust 60 passage on non-condensing engines may be arranged with a special valve operated in any convenient manner to put the exhaust passage near the cylinder in communication with the atmosphere. This makes possible 65 a renewal and a cooling of the contents of the cylinder.

The arrangement is of first importance for locomotives, which must run idle or coast for long periods; but is of significance in the 70 case of stationary engines in that it may avoid the compression and the friction and pulsations of the engine when the live steam is shut off. Portable (locomobile) engines as well as locomotives are at a disadvantage, 75 in that cinders or at least smoke etc. is sucked back into the cylinders, which is done away with by the new arrangement.

The running arrangement as an example is shown in Fig. 1. The inlet valve gear, 80 which is without interest for this invention, consists of valves 5 moved by means of a roller and cam as clearly explained in my Patent No. 1,042,168; Oct. 22, 1912, are situated in the cover 7, of the cylinder 6. The 85 principal outlet takes place through the well known port openings 8 in the middle of the cylinder controlled by means of the working piston 9.

In the vicinity of the ends of the cylinder 90 are arranged outlet valves 10. Each spindle 11 of the valve 10 extends outward through a housing 12 in which an opening spring 13 works upon the same. In the vicinity of the valve 10 the spindle 11 carries a piston 15 95 which moves in a shallow cylinder 17 on the outer cylinder wall. The underside of this piston 15 is in free communication with the common exhaust passage 19 from the auxiliary valves 10. Above the piston 15 100 each cylinder 17 is in direct communication with the inside of the working cylinder 6 through a pipe 20 in such a way that the pipe 20 is located as closely as possible in the vicinity of the corresponding inlet valve 5. According to the drawing the connection 20 105 opens into the pocket 5a of the admission valve.

According to the drawing shown by way of example the auxiliary passages 19 open 110 into the belt 22 from the exhaust ports. The common passage 19 is provided with a spe-

cial valve 23, which is held shut by a loading spring 24. A pressure pipe 25 is connected with an air pressure supply at one end and at the other end with a cylinder containing 5 piston 26. Piston 26 is mounted on the spindle of the valve 23, so that the valve 23 may be opened by means of air pressure during long coasting.

The operation is as follows: During compression and admission the auxiliary valve 10, which remains closed on the side in question, since increasing pressure on the outside of the valve piston 15 through the pipe 20 overcomes the pressure of the opening spring 13. With considerable fall of pressure in the cylinder, during expansion and exhaust, the pressure of spring 13 prevails so that valve 10 opens. During the compression stroke of the piston the valve 10 remains open until the piston has closed the passage 10^a leading from the auxiliary valve to the cylinder. The closure of the valve follows the compression of the remaining steam and the entrance of fresh 25 steam because pressure through the pipe 20 prevails on the auxiliary cylinder 17. If the supply of steam is shut off, either the valves 10 remain full open, or, they close as a result of the compression pressure when 30 the piston has nearly reached the end of its stroke. They open immediately, however, with the returning stroke of the piston, at the latest when the backward movement of the piston opens passage 5^a, and the contents 35 of the cylinder will be forced back and forth through the open valves 10 and the passage 19, the opening of the central valve 23 also removing a tendency to vacuum. If the admission valves are partly throttled a smaller 40 compression will result, because, in coasting, the live steam is shut off. The faults in steam distribution of a link-gear valve are exhaust too far in advance of the end of the stroke, too high compression, and too severe 45 throttling with short admission. If the exhaust lap of the central position of the link gear gives theoretically a compression beginning at 50% stroke, as a result throttling must take place beginning at 70% 50 stroke. From this arises the necessity of providing a large clearance volume with large surfaces, which involve loss, for the introduction of the large quantity of compression steam, so for example, locomotives must 55 have on these grounds according to the initial pressure an injurious clearance chamber of 12 to 14%. The valve gear of stationary engines operated by a movable eccentric and controlled by a shaft governor behaves in 60 the same way as the link gear on locomotives. I avoid these defects by adding to the main valve gear a second outlet organ operated independently by steam pressure. Further, the steam entrance to the second outlet valve loaded on one side by a spring, will

be controlled by the main valve gear, or the link gear of a locomotive, from the main slide valve. Through the second outlet valve the exhaust and compression will be controlled independently of the link gear, and 70 the injurious surfaces and volumes of clearance may be thereby reduced.

The slow opening of the exhaust valve, which occurs in the case of the link gear, at any definite position, may be avoided by 75 the coöperation of the second outlet valve and the enlargement of the outlet opening therewith provided. With regard to the main valve gear, the important consideration enters that the exhaust lap may be 80 greatly increased, so that with cut off at 10%, exhaust will begin at 15% before the end of the stroke or less. This amount of exhaust returns to a normal amount with a longer admission.

The arrangement which is shown by way of example in Figs. 2 and 3, is designed in such a way that the main slide or piston valve controls two special passages 56 which lead the steam to the two special auxiliary 90 slide valves. The link gear, which for simplicity is not shown, operates the main distribution slide valves 31 in the usual way. The entrance of steam to the cylinder 58 occurs through the passage 32. Near the main valve are placed two auxiliary valves 33 which control the passage 34 somewhat removed from the cylinder end. Each valve 31 is designed in piston form as at 33^a and the ring shaped passage 57 of each valve is 100 connected through a pipe 54 with the passage 32, where the pipe enters through the opening 56. On the concave side of the piston web 33^a each valve 33 is loaded by a spring 37. The valve rod carries a housing 53 in which a double acting oil dash-pot is formed with the piston shaped end of the spindle 52.

When the main valve 31 admits live steam into the cylinder, it also admits live steam at the same time by way of 56, 54 into the annular space 57 of the second valve 33. The steam pressure overcomes the pressure of the spring 37 and closes the valve. With the following forward travel of the piston the corresponding valve 31 is closed as soon as the connecting passage 34 is opened by the piston. After closure of the main valve, expansion begins, until the piston uncovers the second passage 34 at the opposite end of the cylinder. The valve 33 belonging to this end is open. Exhaust therefrom follows the uncovering of this port or passage 34. Previously with short admission (early cut off) exhaust would have already taken place through the main valve. With longer admission (later cut off) the main valve holds the outlet still closed, so that exhaust is limited by the second valve. The exhaust takes place through two openings. At the 130

same time at the first end of the cylinder the live steam is released from the annular space 57, whereupon the closing spring opens the opposite outlet valve 33. The returning piston forces the steam out of the cylinder through the main and auxiliary outlet valves. Compression can begin only when the piston has overrun the proper passage 34.

10 Full freedom of adjustment of the lap of the auxiliary valves which depend upon valve 33 according to the lap of the main valve for control of the passage 32 is allowed. For example, the exhaust lap may 15 be made so large that exhaust is limited entirely by the auxiliary valve. According to the drawings there would be a constant compression of 17% and an exhaust of 15% of the stroke (with admission of 10%) 20 which would decrease with increased admission until it was held by the action of the valve 33 at a value of about 6%. As a result of the small volume compressed there is a total volume for clearance losses of 25 about 5% as contrasted with the 14% of the old link gear. Through the reduction of clearance volumes with superheated steam a reduction of steam consumption is obtained which amounts to a mean value 30 of .6 kg. per H. P. hour. Furthermore, a large part of the cooled exhaust steam escapes from the cylinder by way of the auxiliary passages, so that the cooling down of the admission surfaces of the cylinder is in 35 large part avoided. From this results still further conquest over surface losses. Further, a gain in diagram area is achieved from the reduction of exhaust and compression. By the arrangement described, the 40 special outlet passage 34 so adjusts the compression that it gives the utmost reduction of clearance losses under normal operation. With the assistance of the new valve gear a reduction of steam consumption with 45 perheat of 1 to 1.2 kg. per H. P. hour, compared to the known arrangements may be achieved. With saturated steam the gain is actually still greater.

If during coasting of the locomotive the 50 driving steam is shut off, both of the springs 37 hold open the outlet valves 33, and a transfer between the cylinder ends, which may be connected with the atmosphere by means of a special check valve, is so arranged as to prevent the rise of temperature due to the oscillation of the contents of the cylinder.

The auxiliary passages 34 may be located 55 at the same position as the main valve passages 32 in order to reduce still further the clearance losses. Compression is then controlled not by the overrunning of the auxiliary outlet passages by the piston, but by the action of the valve 33 alone. The oil dash pots of the valves 33 limit the extremes

of the strokes and assure noiseless operation. In each dash pot is arranged a suitable ring valve which prevents formation of a vacuum. At the same time the oil dash pot provides lubrication for the valve 70 spindle.

The steam distribution as explained, is such that single admission and, for the greater part of the time, double exhaust have their value, while with ordinary designs, double admission and single exhaust are employed. The new arrangement is in this much more correct, for it is much more difficult to remove the spent steam with its large volume from the cylinder than to 75 introduce the high pressure live steam into the cylinder. A marked reduction of exhaust problems depends upon this. They are still further helped by the ample movement of the auxiliary valve which pumps 80 from end position to end position very quickly during dead center, while time is given without involving undesirable throttling. For example, the auxiliary outlet valve is fully opened on dead center, while 85 at the same time, before the dead center, the other auxiliary outlet valve acted together with the main outlet (exhaust) motion. The closure of the auxiliary valve follows immediately after the piston has closed the 90 auxiliary outlet port. All difficulties with throttling are therefore lacking here.

In place of the auxiliary main valves, any kind of valves and motion may be used, only the method of operating the valve gear is 100 important. The actual design or construction of the valve gear does not matter. The auxiliary outlet valves might be operated by a connection with the corresponding end of the cylinder instead of by a special port 105 covering of the main valve. Also a special governing valve might be used for operating the auxiliary outlet valves.

By allowing free running for down grade the auxiliary outlet valves at the same time 110 remove the additional clearance surfaces and volume losses which are connected with the introduction of a special by pass valve.

Instead of operating the auxiliary outlet valves with the aid of auxiliary springs, some other constant force such as steam or air pressure may be used to control the auxiliary exhaust mechanism. Also the auxiliary exhaust valves could be controlled without the help of a constant force by the 115 arrangement of two pressure chambers, in such a way that each chamber is in communication with that end of the main valve proper to the corresponding end of the cylinder.

With the above described method of operation, both the danger of sucking in of impurities and the cutting of the cylinder, with further cooling off, are prevented. If the link gear is reversed, the outlet valves 120

also automatically reverse and always work as if the link gear valve were entirely laid out. The reversal would take place without any chance of a particular link gear as a result of the indirect dependence upon the main valve motion, and the throttling difficulties which would otherwise be present with a link gear valve motion are completely avoided.

10. What I claim is:—

1. In combination with an engine cylinder having main and auxiliary exhaust ports, a piston operating therein, having piston rings on the hot end thereof which overrun the auxiliary exhaust port, a common outlet passage, automatically operated outlet valves near the cylinder ends, communicating with the common outlet passage, and valve controlling means subject to the steam pressure of the cylinder, whereby the valves open, when the steam supply is cut off.
2. In combination with an engine cylinder, a common outlet passage, automatically operated outlet valves near the cylinder ends, communicating with the common outlet passage, and valve controlling means subject to the steam pressure of the cylinder, whereby the valves open, when the steam supply is cut off to establish communication between the inside of the cylinder on both sides of the working piston.
3. In combination with an engine cylinder having main and auxiliary exhaust ports, a piston operating therein, having piston rings on the hot end thereof which overrun the auxiliary exhaust port, a common outlet passage, automatically operated outlet valves near the cylinder ends, communicating with the common outlet passage, and valve controlling means subject to the steam pressure of the cylinder, whereby the valves open, when the steam supply is cut off, and a mechanically controlled check valve for controlling communication between the common passage and the atmosphere.
4. In combination with an engine cylinder having main and auxiliary exhaust ports, a piston operating therein, having piston rings on the hot end thereof which overrun the auxiliary exhaust port, a common outlet passage, automatically operated outlet valves near the cylinder ends, communicating with the common outlet passage, and valve controlling means subject to the steam pressure of the cylinder, whereby the valves open, when the steam supply is cut off, and a mechanically controlled check valve for controlling communication between the common passage and the exhaust chamber.
5. In combination with a una-directional flow engine cylinder having main and auxiliary exhaust ports, a piston operating therein, having piston rings on the hot end

thereof which overrun the auxiliary exhaust port, a common outlet passage, outlet ports midway the cylinder ends communicating with said passage, automatically operated outlet valves near the cylinder ends also communicating with said common passage, controlling means for said valves, subject to the steam pressure of the cylinder, for opening the valves when the steam supply is cut off.

6. In combination with a una-directional flow engine cylinder having main and auxiliary exhaust ports, a piston operating therein, having piston rings on the hot end thereof which overrun the auxiliary exhaust port, an outlet passage, outlet ports midway the cylinder ends communicating with said passage, automatically operated outlet valves near the cylinder ends, controlling means for said valves, subject to the steam pressure of the cylinder, for opening the valves when the steam supply is cut off as means whereby both ends of the cylinder are put into communication with each other.

7. In combination with a una-directional flow engine cylinder having main and auxiliary exhaust ports, a piston operating therein, having piston rings on the hot end thereof which overrun the auxiliary exhaust port, a common outlet passage, outlet ports midway the cylinder ends communicating with said passage, automatically operated outlet valves near the cylinder ends also communicating with said common passage, controlling means for said valves, subject to the steam pressure of the cylinder, for opening the valves when the steam supply is cut off as means whereby both ends of the cylinder are put into communication with and through the common passage, and a mechanically operated controlling valve for said common outlet passage.

8. An engine cylinder having exhaust ports in the cylinder wall to be uncovered by the piston at or near the end of its working stroke, a passage communicating with the exhaust ports, automatically operated outlet valves near the cylinder ends communicating with the free atmosphere, and valve controlling means subject to the steam pressure of the cylinder, whereby the valves open when the steam supply is cut off.

9. In a steam engine, the combination of a cylinder and a piston working therein, the cylinder having exhaust ports adapted to be uncovered by the piston at or near the end of its stroke and an auxiliary exhaust port near the cylinder end, a valve for controlling said auxiliary exhaust port operated by the steam pressure in one direction and spring pressure in the other, the piston having piston rings on the hot end thereof which overrun the auxiliary exhaust port.

10. In a steam engine, the combination of

a cylinder and a piston working therein, the cylinder having exhaust ports adapted to be uncovered by the piston at or near the end of its stroke, an auxiliary exhaust port near 5 the cylinder end and a valve for controlling said auxiliary exhaust port adapted to be maintained in the closed position against a counteracting force by steam pressure, the piston having piston rings on the hot end 10 thereof which overrun the auxiliary exhaust port.

11. In a steam engine, the combination of a cylinder and a piston working therein, the cylinder having exhaust ports adapted to be 15 uncovered by the piston at or near the end of its stroke, an auxiliary exhaust port near the cylinder end and a valve for controlling said auxiliary exhaust port, adapted to be maintained in the closed position against a 20 counteracting force by the pressure in the cylinder, the piston having piston rings on the hot end thereof which overrun the auxiliary exhaust port.

12. In a steam engine, the combination of 25 a cylinder and a piston working therein, the cylinder having exhaust ports adapted to be uncovered by the piston at or near the end of its stroke, an auxiliary exhaust port near the cylinder end and a valve for controlling 30 said auxiliary exhaust port, adapted to be maintained in the closed position against a counteracting force by steam pressure, said pressure controlled by the steam inlet valve, the piston having piston rings on the hot end 35 thereof which overrun the auxiliary exhaust port.

13. The combination of a steam engine cylinder and a piston working therein, the cylinder having a valve controlled inlet and 40 a valve controlled exhaust at or near the end thereof, means for normally maintaining the exhaust valve open and means operated by the pressure of the live steam for closing the exhaust valve, the piston having piston rings 45 on the hot end thereof which overrun the auxiliary exhaust port.

14. The combination of a steam engine cylinder and a piston working therein, the cylinder having a valve controlled inlet and 50 a valve controlled exhaust at or near the end thereof, means for normally maintaining the exhaust valve open and means operated by the pressure of the live steam controlled by the inlet valve for closing the exhaust valve, 55 the piston having piston rings on the hot end thereof which overrun the auxiliary exhaust port.

15. The combination of a steam engine cylinder and a piston working therein, the cylinder having a valve controlled inlet and 60 a valve controlled exhaust at or near the end thereof, means for normally maintaining the exhaust valve open and means operated by the pressure of the live steam ad-

mitted to the cylinder for closing the exhaust valve, the piston having piston rings 65 on the hot end thereof which overrun the auxiliary exhaust port.

16. A steam engine cylinder and a piston working therein, the cylinder having inlet 70 ports and exhaust ports and valves for controlling the same, the exhaust port valve adapted to be opened by a spring and closed by the pressure of live steam which is controlled by the inlet valve, whereby when the 75 live steam is cut off for coasting, the exhaust valves open, the piston having piston rings on the hot end thereof which overrun the auxiliary exhaust port.

17. A steam engine cylinder and a piston 80 working therein, the cylinder having inlet and exhaust ports, valves for controlling the same, the exhaust port valve adapted to be opened by a spring and closed by the pressure of the steam, which pressure is controlled by the inlet valve, and a suitable valve opening to atmosphere the exhaust 85 spaces or passages, whereby when the live steam is cut off for coasting, the exhaust 90 valves remain open and a tendency to vacuum prevented, the piston having piston rings on the hot end thereof which overrun the auxiliary exhaust port.

18. In combination with a steam engine having a main cylinder and power piston 95 working therein, auxiliary exhaust valve organism comprising a cylinder and piston element, means for leading the live steam thereto to act upon the piston element against a counteracting force, and means 100 whereby the steam inlet valve controls the admission of live steam to said piston and piston element, the power piston having piston rings on the hot end thereof which overrun the auxiliary exhaust port. 105

19. In combination with a steam engine cylinder and a power piston working therein, an auxiliary exhaust valve organism comprising a cylinder and a piston element operating therein, means for establishing communication between said cylinder and piston element, and the head of the engine cylinder, whereby the pressure of the engine cylinder is utilized to actuate the piston element to close the exhaust valve against a 115 counteracting force, the power piston having piston rings on the hot end thereof which overrun the auxiliary exhaust port.

20. In a steam engine, the combination of a double acting cylinder and a piston working therein, the cylinder having exhaust ports adapted to be uncovered by the piston at or near the end of its stroke and an auxiliary exhaust port near the cylinder end, a valve for controlling said auxiliary exhaust 120 port operated by the steam pressure in one direction and spring pressure in the other, the piston having piston rings on the hot 125

end thereof which overrun the auxiliary exhaust port.

21. In a steam engine, the combination of a double acting unaflow cylinder and a piston working therein, the cylinder having exhaust ports adapted to be uncovered by the piston at or near the end of its stroke and an auxiliary exhaust port near the cylinder end, a valve for controlling said auxiliary

port operated by the steam pressure in one direction and spring pressure in the other, the piston having piston rings on the hot end thereof which overrun the auxiliary exhaust port.
